Primary Examiner — Kelley Donnelly(74) *Attorney, Agent, or Firm* — Wilmer Cutler Pickering Hale and Dorr LLP(57) **CLAIM**

The ornamental design for a modular drawer, as shown.

DESCRIPTION

FIG. 1 is a top, front and right side perspective view of a modular drawer showing my new design;

FIG. 2 is a front elevational view thereof;

FIG. 3 is a rear elevational view thereof;

FIG. 4 is a right side elevational view, the left side being a mirror image thereof;

FIG. 5 is a top plan view thereof; and,

FIG. 6 is a bottom plan view thereof.

The broken lines in the figures are for illustration purposes only, and form no part of the claimed invention.
